UNITED STATES PATENT OFFICE.

OSCAR CARLSON, OF BOSTON, MASSACHUSETTS.

BOTTLE STOPPER.

1,425,237.

Specification of Letters Patent. Patented Aug. 8, 1922.

Application filed October 18, 1919. Serial No. 331,667.

To all whom it may concern:

Be it known that I, OSCAR CARLSON, a citizen of the United States, residing at Boston, county of Suffolk, State of Massachusetts, have invented an Improvement in Bottle Stoppers, of which the following description, in connection with the accompanying drawing, is a specification, like characters on the drawing representing like parts.

This invention relates to bottle stoppers of that type adapted to be clamped to the exterior of the neck of a bottle and has for its object to provide a novel bottle stopper which is constructed so that it can be applied equally well to bottles of different sizes and shapes and which is provided with novel means for clamping the stopper to the neck of the bottle.

In order to give an understanding of my invention, I have illustrated in the drawings a selected embodiment thereof which will now be described, after which the novel features will be pointed out in the appended claims.

In the drawings, Fig. 1 is a side view of the neck of a bottle having my improved stopper applied thereto;

Fig. 2 is an enlarged vertical section through the bottle neck with the stopper applied taken on substantially the line 2—2, Figs. 1 and 3;

Fig. 3 is an underside view of the bottle stopper shown in Fig. 2 with the bottle removed;

Fig. 4 is a view similar to Fig. 2 taken on the line 4—4, Fig. 3;

Fig. 5 shows the parts of the bottle stopper when it is being applied to the bottle;

Fig. 6 is a section on the line 6—6, Fig. 3;

Fig. 7 is a view similar to Fig. 3 showing the clamping member unclamped;

Fig. 8 is a side view of the seat member removed;

Fig. 9 is a section on the line 9—9, Fig. 2.

My improved bottle stopper comprises a seat member to rest against the end of the bottle neck and provided with spring fingers to engage the bead at said neck, and a clamping member to encircle the fingers and adapted by its turning movement to clamp the fingers firmly against and under the bead.

I have shown at 1 the neck of a bottle

to which my bottle stopper is to be applied, said bottle neck 1 having the usual bead 2 at its end.

The seat member of my improved bottle stopper is indicated generally at 3 and it comprises a body portion to rest against the end of the bottle neck, and a plurality of spring fingers 4 adapted to embrace the bead 2 of the bottle neck. The seat member 3 preferably has associated therewith a washer 15 of some suitable packing material which makes a tight joint with the end of the bottle neck. The resilient fingers 4 extend below the seat member 3 and are formed at their lower end with bead-engaging portions 5 adapted to fit underneath the bead 2, and in order to give these fingers 4 sufficient resiliency, I propose to make them with the reverse or U-shaped bend 6 so that each finger extends upwardly from the seat member and then is bent back on itself and extends down below the seat member and terminates in the bead-engaging portion 5. The seat member is also preferably formed centrally with the stem portion 7.

The clamping member is indicated at 8 and is an annular member which surrounds the fingers 4. This clamping member is in the form of a cap and the central portion thereof is bent inwardly, as shown at 9, and is provided with an aperture 10 through which the stem 7 projects, the outer end of the stem preferably being enlarged, as shown at 11, so as to prevent the two parts of the bottle stopper from becoming separated. The clamping member is thus free to slide up and down on the stem. Said clamping member is capable of turning relative to the seat member and has formed in its side a plurality of cam portions 12 which are adapted to engage the fingers 4 and clamp them firmly against and underneath the bead 2 as the clamping member is turned.

When the bottle cap is to be applied to a bottle the clamping member will be turned into the position shown in Fig. 7 so that the fingers are situated between the cam portions 12. The stopper may be then applied to the bottle neck, the resiliency of the fingers 4 permitting the bead-engaging portions 5 to pass over the bead. After the seat member has been firmly seated against the end of the bottle neck, as shown in Fig. 4, the clamping member is then turned

thereby bringing the cam portions 12 against the fingers and clamping the fingers firmly against and beneath the bead 2, as shown in Figs. 2 and 6. The cam members are shaped 5 to engage the fingers opposite the bead-engaging portions 5 thereof so that the action of the cam comes on the portion of the fingers situated beneath the bead 2. The bottle stopper will thus be firmly clamped to 10 the bottle, and this same action will take place even though the size of the bottle and the shape of the bead vary somewhat because the resiliency of the fingers 4 will permit them to be applied to bottles of different 15 sizes, and the cams are of sufficient extent so that they will act to clamp the fingers tightly to bottles which vary in size somewhat.

The stopper can be removed from the bottle by merely turning the clamping member from its clamping position shown in Fig. 3 to its non-clamping position shown in Fig. 7, thus removing the clamping pressure from the fingers, after which the stopper 25 can be pulled off the bottle.

In applying the stopper to some bottle necks it may be desirable to first push the seat member downwardly relative to the clamping member, as shown in Fig. 6, thus to give the fingers 4 greater freedom of movement to snap over the bead of the bottle, and after the seat member has been brought against the neck of the bottle, then the clamping member may be pushed downwardly into the position shown in Fig. 4 and turned to clamp the fingers to the neck of the bottle, as shown in Figs. 2 and 6.

I have above referred to my device as a bottle stopper because I have shown it as used for stopping or closing a bottle, but so far as the invention is concerned it is 40 equally well adapted for use in stopping or

closing other receptacles than bottles, such, for instance, as cans, tanks which have a neck provided with a bead, automobile radiators or any other similar article. Therefore, although I have used the term bottle stopper in the claims and specification, I do not wish to be limited to the use of the invention as a bottle stopper. 45 50 55

I claim:

1. In a bottle stopper, the combination with a seat member to rest on the end of a bottle neck and having integral therewith a plurality of spring fingers to engage the bead of said bottle neck, and also having a headed stem extending therefrom, of a clamping member swivelled on said stem and capable of moving longitudinally thereof without turning thereabout, said clamping member being provided with cam portions which are brought, by the movement of said clamping member longitudinally of the stem, into a position to engage the fingers below the bead, turning movement of the clamping member causing the cam portions to clamp the fingers about the bead. 60 65

2. In a bottle stopper, the combination with a seat member to rest on the end of a bottle neck and having a plurality of spring fingers to engage the bead of said bottle neck, of a cup-shaped clamping member swivelled on said stem and capable of moving longitudinally thereof without turning thereabout, said clamping member encircling said fingers and being provided with cam portions, which are brought by the movement of said clamping member longitudinally of the stem into position to act on the fingers beneath the bead as the clamping member is turned. 70 75 80

In testimony whereof I have signed my name to this specification.

OSCAR CARLSON.
